LOOM WITH STATIONARY WEFT SUPPLY

Charles Clutsom, St. Michaels, Ashby-de-la-Zouch, England

Application November 18, 1938, Serial No. 241,278
In Great Britain December 3, 1937

8 Claims. (Cl. 139—124)

This invention relates to looms with stationary weft supplies, i. e. shuttleless looms with weft supplies which are stationary as regards insertion of the weft, for weaving smallware, for example elastic and inelastic or so-called rigid webs and like narrow pieces such as ribbons and braids in continuous length, as well as for weaving wider elastic fabrics, e. g. upwards of 12 inches or more in width, for manufacture subsequently into garments such as corsets, corselettes, belts, girdles and like foundation garments, and rigid pieces for other purposes.

The present invention is applicable to looms which include a weft laying member or members consisting of a thread guide or guides adapted to operate to carry the weft to and fro through a shed or sheds of warps, and a thread engaging element or elements adapted to operate in conjunction with the weft laying member or members to ensure laying of the thread to and fro through the shed or sheds or/and to form a selvedge or selvedges, such looms hereinafter being referred to as "looms of the kind herein referred to."

In this respect the invention is intended for application principally to looms of the form described in the specification of my prior Letters Patent No. 2,130,636.

The present invention comprises an improvement the object of which is to facilitate satisfactory functioning of the thread engaging element or elements.

The invention is advantageously applicable to a loom of the kind herein referred to wherein the thread engaging element or elements is or are adapted to operate in such a manner as to form a selvedge or selvedges on the adjacent edge or edges of the fabric, for example a loom in which the thread engaging element consists of a loop forming instrument, such as a latch needle, whereby loops formed by successive pairs of wefts are interknit to form a selvedge as weaving proceeds.

In order that the invention may be more clearly understood and readily carried into practical effect there will now be described with reference to the accompanying drawings a particular illustrative embodiment of the invention as applied for use in conjunction with a pivoted weft laying member and a reciprocatory latch needle operating in a horizontal plane, the said needle being mounted for reciprocation alongside the path of the warps so as to engage the weft presented by the weft laying member operating from the opposite side of the path of the warps in order to knit a selvedge

from the weft, as described in the specification hereinbefore referred to.

In the drawings,

Figure 1 is a plan view of a unit or attachment incorporating the aforesaid pivoted weft laying member, the reciprocatory latch needle and means constructed in accordance with the present invention for the purpose hereinbefore alluded to.

Figure 2 is a side elevational view of the same.

Figure 3 is an end view as viewed in the direction of the arrow A in Figure 1.

Figures 4 and 5 are detail side and end elevational views respectively of so much of the said unit or attachment as is necessary to illustrate the manner in which the means provided by the invention function to hold back the inserted weft while the latch needle is advanced to engage the weft thread.

Figures 6 and 7 are two views similar to Figures 4 and 5 showing the relative position of the parts when the needle has completed its advancing movement.

Figure 8 is an enlarged detail plan view illustrative of the manner in which a previously formed portion of the selvedge is held back while the needle advances.

Like parts are designated by similar reference characters throughout the drawings.

The particular form of unit or attachment shown in Figures 1-3 is similar to that described in the specification aforesaid and, as will be seen, the weft laying member 1 and the knitting needle 2 are mounted for movement upon a common bracket or support 3 adapted to be applied to and removed from a loom. In Figure 2 the unit or attachment is indicated as being secured to the top of a longitudinal frame member 4 of a loom. The weft laying member is in the form of a thread guide which is carried by, or formed integrally with, a substantially radial arm 5 pivotally mounted at 6 on the bracket or support so as to enable it to be oscillated in a horizontal plane. The necessary movements may conveniently be imparted to the member 1 by a cam actuated slide bar furnished with pins or the equivalent between which the rear end of the arm 5 is located, all as fully described in my prior specification aforesaid. The latch needle 2 is attached to a carrier bar 7 slidably mounted for reciprocation on the bracket or support 3 and located at the side of the latter remote from the pivot 6 between two plates 8 and 9 which together constitute a guide for the bar. The said bar is provided with an operating stud 10 by means of which it can be reciprocated, e. g. from a cam actuated rockshaft 55

through intermediate connections such as those indicated in dot-and-dash lines at 11 and 12 in Figure 2. In the drawings the weft supplied to the weft laying member 1 is indicated at a and the 5 said member and the needle 2 are located on opposite sides of the path of the warps b. The curved portion of the member 1 can therefore carry weft to and fro through a shed c (Figures 2, 4 and 6) formed in the usual manner. The 10 needle 2 is mounted for reciprocation alongside the path of the warps and at the completion of each advancing or forward movement thereof engages the weft presented to it by the member 1. A slotted guide 13 is conveniently provided for 15 constraining the fabric d (Figure 1) as it is woven to maintain a definite path in the region of the fell e. For the purpose of the present description no further details of this particular unit or attachment are necessary and the manner in which 20 the latter operates to produce a plain weave with a knitted selvedge f is fully described in my prior specification.

In accordance with the present invention there is provided a member 14 like a pin or small finger 25 mounted for movement towards and from the fell e of the fabric d at right angles to the inserted weft, or substantially so, between the latch needle 2 and the adjacent warp b' (see Figure 1), the arrangement being such that the pin or finger 30 moves towards the said fell to hold back the inserted picks g and h of weft while the needle 2 is advanced to engage the weft thread when next presented to it by the weft laying member 1. The effect, as shown more clearly in Figure 8, is that a 35 loop f' of the selvedge already on the needle is held back on the needle stem 2a while the needle advances to engage the weft thread preparatory to forming the next loop of the selvedge, and so on as weaving proceeds. For this reason it is 40 convenient to arrange the pin or finger 14 for operation from the needle carrier bar 7 so that the said pin or member operates in proper timed relation with the needle 2. In this connection the said pin or finger is conveniently mounted in or 45 on one end of a two-armed lever 15 which is pivotally mounted alongside the needle carrier bar 7 so as to rock in a vertical plane and is slotted longitudinally as indicated at 16 on the side of the pivot 17 remote from the pin or finger 14 for reception of the operating stud 10 aforesaid, the 50 slot being straight for the major portion of its length and curved downwards at the outer end, i. e. the end remote from the pivot 17, whereby when the needle bar is reciprocated the lever 15 is oscillated. That is to say, when the needle is 55 advanced the stud 10 first moves along the curved part 16a of the slot 16 so that the lever 15 is depressed at this end thereby lifting the opposite end so that the pin or finger 14 is brought up (from 60 the position shown in Figures 2 and 3) to the fell e of the fabric in the manner represented in Figures 4 and 5, whereafter the stud moves along the straight part 16b of the slot thereby holding the pin or finger in this position until the needle 65 has completed its advancing movement. It is convenient to mention here that towards the end of this advancing movement the bar 7 preferably makes contact with a cam 18 whereby the needle is deflected as shown in Figures 6 and 7 to facilitate engagement thereof with the weft thread 70 presented to it at this stage by the weft laying member 1 in the manner described in the hereinbefore mentioned prior specification. Upon reverse movement of the bar 7 to retract the needle 2, the stud 10 moves along the straight part 16a

of the slot and then along the downwardly curved part 16b thereby, towards the end of its movement, rocking the lever 15 in the reverse manner to remove, i. e. lower, the pin or finger 14 from the fell e so as to enable the pair of weft picks last laid 5 to be pulled up to the fell. The pin or finger is located in a part 19 bent or attached, e. g. by screws 20, at right angles to the lever 15 so as to project laterally therefrom, and the pin or finger is also bent or cranked laterally in the manner shown 10 in Figures 3, 5 and 7 so as to enable it to work between the path of the needle 2 and the adjacent warp thread b'. In the specific example illustrated the pin or finger consists of a short piece of wire which is appropriately bent to shape and 15 secured in the part 19 by means of a screw 21, although a pin or finger of any other suitable character and fixed in position in any other convenient way may, if desired, be adopted. In the arrangement described, therefore, the pin or finger 20 14 engages the inserted weft between the loop f' on the needle and the last mentioned warp thread (see more particularly Figure 1). If desired the arrangement may be such that the pin or finger 25 operates with a pushing or pressing action upon the weft. Instead of being actuated positively in each direction the lever 15 may be moved in one direction by the stud 10 working on a cam-shaped part on the lever, or by a cam suitably applied, and in the other direction by a spring. As a further alternative the said lever may be operated independently of the needle by cam, crank, eccentric or any other suitable means, and may be positively actuated in each direction or positively actuated in one direction and spring actuated in 30 the other direction. Operation of the pin or finger independently of the needle might sometimes be advantageous in that it would readily permit of adjustments being made in the timing of the operation of the pin or finger in relation to 35 the forward and reverse movements of the needle. 40

The pivot pin or stud 17 for the lever 15 is conveniently mounted, either fixedly or adjustably, in the outer of the two guide plates 8 and 9 so that the lever is located on the outside of the 45 needle 2. A collar 22 which is fixed upon the outer end of the pivot pin or stud 17, e. g. by means of a screw 23, serves to prevent lateral displacement of the lever 15 although such displacement may, if desired, be prevented in any other 50 suitable manner.

A brush for ensuring that the latch 24 of the needle is open at appropriate times is designated by the reference numeral 25 but has been broken away in Figure 1. 55

The arrangement specifically described is adapted for producing a fabric with a single weft and a single weft locking selvedge on the appropriate edge.

A pin or finger and lever arrangement of the 60 character aforesaid may, of course, be provided in conjunction with each of two or more needles co-operating with the same weft laying member but on opposite sides of the path of the warps so that a selvedge is formed at each edge of the fabric, 65 and a similar arrangement or arrangements may be provided in conjunction with one or more needles co-operating with a pair of weft laying members to produce double faced fabric with a locking selvedge or selvedges. 70

Any convenient number of units or sets of mechanism including one or more weft laying members, one or more thread engaging elements and corresponding means constructed, arranged and adapted for use according to the present inven- 75

tion, may be provided in one loom for weaving several or numerous pieces of fabric face to face, e. g. one above another, or side by side, according to requirements.

5. The invention is applicable for use in conjunction with an arrangement wherein an additional thread or threads is or are supplied to the thread engaging element or elements and thereby inter-looped or interknitted with the weft to make a fast 10 selvedge or selvedges.

As will be understood from the foregoing description, the expression "weft" is to be regarded as covering either a single weft thread or a plurality of such threads where the context so admits.

15. What I claim then is:

1. In a weaving loom with a stationary weft supply, in combination, a weft laying member consisting of a thread guide adapted to operate to carry the weft to and fro through a shed of 20 warps, a movable thread engaging element adapted to operate in conjunction with the weft laying member to ensure laying of the thread to and fro through the shed and to facilitate formation of a selvedge at an edge of the fabric 25 being woven, and a member arranged for movement at right angles to the inserted weft towards and from the fell of the fabric at one side thereof in close proximity to the outermost warp for the purpose of holding back the inserted weft while 30 the thread engaging element is moved to engage the appropriate thread.

2. In a weaving loom with a stationary weft supply, in combination, a weft laying member consisting of a thread guide adapted to operate to carry the weft to and fro through a shed of 35 warps, a movable thread engaging element adapted to operate in conjunction with the weft laying member to ensure laying of the thread to and fro through the shed and to facilitate formation of a selvedge at an edge of the fabric 40 being woven, means associated with the thread engaging element whereby the latter can be operated, a member arranged for movement towards and from the fell of the fabric at one 45 side thereof adjacent to the outermost warp for the purpose of holding back the inserted weft while the thread engaging element is moved to engage the appropriate thread, and means for effecting movement of the aforesaid member from 50 the means associated with the thread engaging element in timed relation with said element.

3. In a weaving loom with a stationary weft supply, in combination, a weft laying member consisting of a thread guide adapted to operate to carry the weft to and fro through a shed of 55 warps, a reciprocatory loop forming instrument disposed alongside the path of the warps and adapted to engage the weft presented by the weft laying member in order to knit therefrom a selvedge at an edge of the fabric being woven, a member mounted for movement towards and from the fell of the fabric between the loop forming instrument and the adjacent warp, and means for so operating said member in timed 60 relation with the loop forming instrument that it moves towards the fell to hold the inserted weft back each time said instrument is advanced to engage the weft thread presented to it by the weft laying member, for the purpose herein specified.

4. In a weaving loom with a stationary weft supply, in combination, a weft laying member consisting of a thread guide adapted to operate to carry the weft to and fro through a shed of 65 warps, a thread engaging element, a part for car-

rying said element, said part being adapted to be reciprocated alongside the path of the warps, and the thread engaging element being adapted to engage the weft presented by the weft laying member in order to form from said weft a selvedge at an edge of the fabric being woven, a member mounted for movement towards and from the fell of the fabric between the thread engaging element and the adjacent warp, and means for operating said member from the part 10 by which the thread engaging element is carried, the timing of the parts being such that said member moves towards the fell to hold the inserted weft back while the thread engaging element is advanced to engage the weft thread presented 15 to it by the weft laying member, for the purpose herein specified.

5. In a weaving loom with a stationary weft supply, in combination, a weft laying member consisting of a thread guide adapted to operate 20 to carry the weft to and fro through a shed of warps, a guide, a thread engaging element attached to a carrier bar slidably mounted for reciprocation in said guide, said thread engaging element being adapted to operate in conjunction 25 with the weft laying member to ensure laying of the weft to and fro through the shed and to form a selvedge at an edge of the fabric being woven, an operating stud on said carrier bar whereby the latter is operated, a member mounted for 30 movement towards and from the fell of the fabric between the thread engaging element and the adjacent warp, a lever in which said member is secured, said lever being movably mounted alongside the carrier bar and slotted for reception of 35 the aforesaid operating stud, the construction and arrangement being such that said member moves towards the fell to hold the inserted weft back whenever the thread engaging element is advanced to engage the weft thread presented to it 40 by the weft laying member, for the purpose herein specified.

6. In a weaving loom with a stationary weft supply, in combination, a weft laying member consisting of a thread guide adapted to operate 45 to carry the weft to and fro through a shed of warps, a guide, a thread engaging element attached to a carrier bar slidably mounted for reciprocation in said guide, said thread engaging element being adapted to operate in conjunction 50 with the weft laying member to ensure laying of the weft to and fro through the shed and to form a selvedge at an edge of the fabric being woven, an operating stud on said carrier bar whereby the latter is operated, a member mounted for movement towards and from the fell of the fabric between the thread engaging element and the adjacent warp, a two-armed lever in one end of 55 which said member is provided, said lever being pivotally mounted alongside the carrier bar and slotted on the side of the pivot remote from said member for reception of the aforesaid operating stud, whereby when the carrier bar is reciprocated the lever is oscillated and said member moves towards the fell to hold the inserted weft back whenever the thread engaging element is advanced to engage the weft thread presented to it by the weft laying member, for the purpose 60 herein specified.

7. In a weaving loom with a stationary weft supply, in combination, a weft laying member consisting of a thread guide adapted to operate 70 to carry the weft to and fro through a shed of warps, a guide, a thread engaging element attached to a carrier bar slidably mounted for re- 75

- 5 ciprocation in said guide, said thread engaging element being adapted to operate in conjunction with the weft laying member to ensure laying of the weft to and fro through the shed and to form a selvedge at an edge of the fabric being woven, an operating stud on said carrier bar whereby the latter is operated, a member mounted for movement towards and from the fell of the fabric and bent laterally so as to enable it to work between the path of the thread engaging element and the adjacent warp, a lever having at right angles thereto a part in which said member is provided, said lever being movably mounted alongside the carrier bar and slotted for reception 10 of the aforesaid operating stud, the construction and arrangement being such that said member moves towards the fell to hold the inserted weft back whenever the thread engaging element is advanced to engage the weft thread presented to it by the weft laying member, for the purpose herein specified.
- 10 15 20 25 8. In a weaving loom with a stationary weft supply, in combination, a weft laying member consisting of a thread guide adapted to operate

to carry the weft to and fro through a shed of warps, two guide plates from the outer of which projects a pivot, a thread engaging element attached to a carrier bar which is slidably mounted for reciprocation between said plates, said thread engaging element being adapted to operate in conjunction with the weft laying member to ensure laying of the weft to and fro through the shed and to form a selvedge at an edge of the fabric being woven, an operating stud on said carrier bar whereby the latter is operated, a member mounted for movement towards and from the fell of the fabric between the thread engaging element and the adjacent warp, a lever by which said member is carried, said lever being pivotally mounted upon the aforesaid pivot alongside the carrier bar and slotted for reception of the operating stud, the construction and arrangement being such that said member moves towards the fell to hold the inserted weft back whenever the thread engaging element is advanced to engage the weft thread presented to it by the weft laying member.

CHARLES CLUTSOM.
